UNITED STATES PATENT OFFICE.

WILLIAM S. STEWART, OF BISBEE, ARIZONA TERRITORY, ASSIGNOR OF
ONE-HALF TO H. J. DAY, OF BISBEE, ARIZONA TERRITORY.

OIL-BURNER.

No. 841,597.

Specification of Letters Patent.

Patented Jan. 15, 1907.

Application filed May 19, 1906. Serial No. 317,800.

To all whom it may concern:

Be it known that I, WILLIAM S. STEWART, a citizen of the United States, residing at Bisbee, in the county of Cochise and Territory of Arizona, have invented certain new and useful Improvements in Oil-Burners, of which the following is a specification.

This invention relates to new and useful improvements in liquid-fuel burners; and it relates particularly to a type of burner in which the combustion of the oils is facilitated by the admixture of steam.

In this connection the invention aims, primarily, to provide a device which shall insure a perfect combustion of the liquid fuel and in which the oil and steam are so distributed that the latter acts as a vehicle for the former and serves as an insulation for the walls of the furnace until the mixture of oil and steam shall have penetrated a sufficient distance therein to come into contact with the flames. The advantages attained from this mode of use are that the steam serves as an oil insulation for the walls of the furnace and prevents any oil from settling thereupon, with the resultant carbonization thereof. In its initial passage into the furnace the steam serves as a vehicle for the oil and instead of being thoroughly mixed therewith surrounds the same; but as the mixture after leaving the burner travels through the furnace the heat insures a thorough atomization of the particles, so that at the time of meeting the flames a perfect combustion of the fuel is assured without any premature carbonization thereof upon the walls of the furnace.

The detailed construction will appear in the course of the following description, in which reference is had to the accompanying drawings, forming a part of this specification, like numerals designating like parts throughout the several views, wherein—

Figure 1 is a side elevation showing an oil-burner constructed in accordance with the present invention. Fig. 2 is a fragmentary longitudinal section thereof. Fig. 3 is a longitudinal section of a detached element to be hereinafter specifically referred to, and Figs. 4 and 5 are respective front and end elevations thereof.

In the practical embodiment of my invention I employ a burner A, designed for the admixture of steam and oil and in commun-

cation independently with a steam-pipe 1 and an oil-pipe 2, surrounding the same in spaced concentric relation, so that an annular passage 3, parallel with the longitudinal axis of said pipes, is afforded therebetween. The steam-pipe 1 has connection with a pipe 4, leading from a source of steam-supply having an independent pressure, and the oil-pipe 2 has connection with a pipe 5, leading from a source of oil-supply having an independent pressure. The pipe 4 is joined with the pipe 5 by a branch pipe 6, which is provided with a manually-operated controlling-valve 7. When the valve 7 is opened, the pipe 6 affords communication between the pipes 4 and 5, so that the steam passes therethrough without entering the burner and exerts a suction in the pipe 1 that tends to clean the same out when the burner is not in use, so as to prevent the apparatus from becoming clogged by extraneous matter. The steam admitted through the valve 7 in its blowing-passage through the pipe 3 tends to clean the latter positively, as will be readily understood.

The pipe 1 projects a short distance beyond the pipe 2 at its outer end and is threaded, as at 8. The pipe 2 is likewise threaded at its extremity, as at 9. The pipes 1 and 2 have connection by virtue of their threaded portions 8 and 9 with correspondingly-arranged threaded recesses in the enlarged end of a burner-head 10. The burner-head 10 is of substantial L shape in cross-section and is provided with an inclined passage 11, leading from the pipe 1 to the horizontal face thereof, and with a horizontal passage 12, leading from the passage 3 of the pipe 2 to the vertical face thereof. The head 10 is provided at the junction of its angularly-disposed faces with an interfitting cap 13, suitably secured thereon and illustrated in detail in Figs. 3, 4, and 5. The admixture of the steam and oil to the degree requisite for carrying out the functions of the invention is effected within the cap 13, and to this end said cap is formed with a substantially wedge-shaped passage 14, tapering rearwardly and confronting the horizontal face of the head 10, so that said head and said cap unite to form a continuous fluid-conducting passage throughout the lineal extent of the cap 13, said passage being in communication at its rear end with the

passage 11. The passage 14 is intersected at an approximately central point by an inclined passage 15, formed in the cap 13 and communicating at its rear end with the passage 12.

In practical use the steam travels through the pipe 1 at a much greater relative pressure than that of the oil traveling through the passage 3. The oil in its travel through said passage is heated by the steam in the pipe 1 to a degree approximating the heat of said steam. The steam from the pipe 1 passes through the passage 11 into the passage 14 in the cap 13. The oil in like manner passes at less speed through the passage 3 and the passage 12 into the passage 15 in the cap 13, by which it is conducted into the passage 14. Inasmuch as the oil has an independent reduced pressure and is not dependent for its travel upon the suction of the steam, and inasmuch as the passage 14 constantly widens toward its outlet, the steam and oil therein are not choked, but move freely therethrough without becoming thoroughly intermixed. The jet of steam catches the oil as it leaves the passage 15 and conveys it through the burner-tip of any approved form into the furnace. Hence it is seen that the arrangement of the parts is such that the steam serves initially as a vehicle for the oil until the time for its proper commingling therewith in establishing a perfect combustion. It will be readily apparent that the steam in serving as a vehicle and in being projected into the furnace in relatively greater quantities than the oil also serves as an insulating-envelop to protect the walls of the

furnace from the particles of oil settling thereupon and being carbonized.

While the elements herein shown and described are well adapted to serve the purposes set forth, it is obvious that various minor changes may be made in the proportions, shape, and arrangement of the several parts without departing from the spirit and scope 45 of the invention as defined in the appended claim.

Having fully described my invention, I claim—

In an oil-burner, the combination with an 50 inner steam-pipe and an outer concentric oil-pipe of a burner-head formed with concentric threaded openings for the reception of said respective steam and oil pipes, said burner-head comprising a major section 55 formed with a horizontal passage communicating with said oil-pipe, a flared recess extending to the front edge thereof and an inclined passage leading rearwardly from said recess to said steam-pipe and a section superimposed on said first-named section and formed throughout its lineal extent with a flared recess, adjacent to and coacting with said first-named flared recess to form a flared discharge-passage and formed with an inclined passage leading from a point within said flared recess to said horizontal passage in said first-named section.

In testimony whereof I affix my signature in presence of two witnesses.

WILLIAM S. STEWART.
